(57) **CLAIM**

I claim the ornamental design for a game table, as shown and described.

DESCRIPTION

FIG. 1 is a front, left side perspective view of the game table, showing our new design;

FIG. 2 is a left side view thereof;

FIG. 3 is a right side view thereof;

FIG. 4 is a top plan view thereof;

FIG. 5 is a bottom plan view thereof;

FIG. 6 is a front plan view thereof; and,

FIG. 7 is a rear plan view thereof.

The broken lines of the drawings illustrate portions of the game table that form no part of the claim.

1 Claim, 7 Drawing Sheets
